CABLE MUNITION

Nicholas W. Brett, Baltimore, and Royale R. Crabtree, Towson, Md., assignors to the United States of America as represented by the Secretary of the Army

Filed Jan. 19, 1965, Ser. No. 426,698
3 Claims. (Cl. 102—23)

The invention described herein may be manufactured and used by or for the Government for governmental purposes, without the payment to us of any royalty thereon.

This invention is a method of achieving an extended line source of a chemical agent cloud or aerosol.

The principal object of this invention is to provide a cable containing a lethal capability that is appreciably reduced in weight to permit an increase in the payload of chemical agent.

It is a further object to make this cable of extreme length and arranged so that it may be dispensed lengthwise at the target area from a moving conveyance preferably from the air.

It is another object to provide a light flexible covering for the cable so that it may be coiled on reels and readily dispensed.

The invention will be better understood by reference to the drawings in which:

FIGURE 1 is a diagrammatic view of the cable broken in the center to show it may be of an indeterminate length; and

FIGURE 2 is a cross-sectional view taken on line 2—2 of FIGURE 1.

The cable has a light flexible outside cover 3 that is readily ruptured when ignited from the inside. The Prima Cord or pyro cord 4 is within the cable and extends the full length of the cover 3 and may be located in the center as shown or off-center or even on the outside of the cable cover. The remaining space is filled with the destructive chemical compound 5 which may be in a powdered, granulated, plasticized or liquid form. Attached to the Prima Cord 4 is a fuze 6 which may be attached to one end, if that end of the cable be in close proximity so that a convenient connection may be made or a self-detonating fuze may be attached to both ends if the cable is laid in a remote area. A fuze at both ends has the advantage in that the effect may not be lessened, by accidentally or otherwise, severing the cable, it will still be initiated and fired from both ends.

Thus, cable munition takes the form of a thin walled flexible tube containing a chemical agent and a Prima Cord which extends the entire length of the munition. The covering for this munition must also be resistant to the contained chemical agent and strong enough to permit coiling and winding without breakage. Materials such as rubber or polyethylene are excellent and lend themselves to continuous extrusion which is very desirable for efficient production. It is contemplated that the cable munition when produced will be cut in lengths of 500 or 1000 feet and wound on suitable spools. The Prima Cord or pyro cord is available in various sizes, is considered safe for handling and possesses a good tensile strength which is desirable for this use.

The agent used in this cable munition may be a chemical for smoke, gas, bacteria, fire or high power explosive such as granulated TNT or plasticized explosives. For a pyrotechnic chemical the cable may be filled with napalm, jellied gasoline or a thermite fill.

2

The cable munition could be laid by hand for perimeter defense or laid at right angles for a complete cross-sectional coverage. It also could be laid from truck, jeeps or tanks by unreeling the spools on which the cable is wound. Such action would be initiated to repel an expected attack. It is contemplated that this cable munition may be more readily laid from an air conveyance from which reels of the cable would be suspended and free to unwind, while the reels would be spaced according to the desired pattern. Also after the cables were laid from the air in spaced relation or approximately parallel to each other, another set could be laid at right angles to the first set so that that cross-sectional pattern would provide more complete coverage. Upon initiation the munition will form an unbroken curtain of fire, smoke, toxic or an incapacitating agent for either offensive or defensive tactics. Cables carrying such a chemical agent could be air dropped over bridges, ships or buildings with the contemplation that these objects would be completely and accurately destroyed. Where desirable a pyrotechnic fill would produce, if desired, continuous walls of fire the length of the cable dropped. Such cable could also be employed for riot control without fear of damage due to falling hardware.

The advantages of this weapon are its versatility with respect to both employment and the type of chemical agent utilized. By reducing the hardware, the overall weight is greatly reduced and the resulting increase in efficiency makes it much more desirable as an airborne munition than older types. It is also advantageous that this cable munition may be used as a completely nonlethal riot control weapon by reason of the ease of handling and delivery.

What is claimed is:

1. A cable of indeterminate length comprising a line with a flexible covering adapted to be coiled on a reel and rupturable on detonation, a Prima Cord within said flexible cover extending the full length thereof, a chemical agent with a lethal capability filling the remaining space within the cable, self-detonating fuzes attached to both ends of said Prima Cord to insure complete detonation upon a break in the cable, said cable adapted to be placed in operative position by unreeling from an air or land conveyance and on detonation rupturing the flexible cover to release the lethal chemical agent throughout the entire length of the cable.

2. A method of laying waste to a designated area which comprises laying single strands of explosive cable of indeterminate length having self-detonating fuzes at opposite ends and containing a chemical agent with a lethal capability by unreeling from a conveyance and detonating the explosive cable to insure upon a break in the cable the release of the lethal chemical agent throughout the entire length of the cable.

3. A method of covering a designated target area which comprises, coiling single strands of cable containing a lethal chemical agent having self-detonating fuzes at opposite ends on spools attached to an air conveyance in a spaced relation, laying said strands of cable having a lethal capability across said area in same relation as said spools by unreeling from the air and thereafter detonating the cable at both ends as laid to insure upon a break in the cable the release of the lethal chemical agent throughout the entire length of the cable in the target area.
